UNITED STATES PATENT OFFICE.

LOUIS WITTBOLD, OF CHICAGO, ILLINOIS.

FLORAL DISPLAY STAND.

Application filed May 7, 1923. Serial No. 327,256.

This invention relates to a stand whereon may be mounted a floral display, be it palms, ferns, flowers, or what not. More particularly it is designed for displays which are somewhat large and heavy, and in consequence, difficult to move and set up. The object of the present invention is, therefore, to provide a stand for the purposes named, which will be ornamental in appearance, 10 easily disassembled, when required, and conveniently manipulated when fresh water is to be added.

Such a stand is illustrated in the accompanying drawing which is a view in elevation with a portion broken away so as to show in section certain parts which normally are hidden.

The floral display here shown may comprise one or more palms and ferns having 20 their roots contained within an earth-filled pot, tub, or vessel A. The walls 1 of such a pot are usually tapered outwardly and, of course, are unsightly to the eye as ordinarily made. A pan B underlies the bottom 25 of the pot 2 through which water is permitted to escape as by means of openings 3. Parts such as these are in common use and, unless dressed up by a suitable cover, or otherwise, must necessarily detract from the 30 appearance of the floral display.

According to this invention a stand is provided consisting of two separable parts—a pedestal C and pot cover D in the general 35 form of a shell. As shown, a stand of this kind may be formed of wicker with a contour which is both attractive and suitable for the purpose intended. The pedestal has the usual base 5 and a head 6 which is provided with an upstanding peripheral wall 7, 40 as shown. Below the upper edge of the wall is a shelf 8 that is suitably carried in the head, this shelf being adapted to support the pan B whose diameter is appreciably less than that of the circular wall 7. The 45 pot bottom 2 is also, by preference, of less diameter than the pan, and it is even desirable for beauty of lines that the widest diameter of the pot should not exceed that of the pan B so as to permit of the use of 50 a cover D whose walls 9 are tapered inwardly but with an outward flare 10 at the base. This cover may be rested directly upon the wall 7 of the pedestal, or upon the upper edge of the pan, or both, and 55 may be adapted to so co-operate with these

parts by properly shaping its flaring base 10 for this purpose.

A stand answering to this description is first assembled with the pedestal cover and pan in place, and the pot is then lowered 60 into position. The cover which is loose at all times may be raised slightly whenever desired for inspection of the water level within the pan. In fact, water may be 65 poured directly into the pan, if desired, by lifting the cover sufficiently for this purpose, but this utility is not intended to substitute for the application of water to the plant in the usual manner.

It will be noted that the cover extends up 70 beyond the upper edge of the pot so as to thoroughly conceal its appearance. This, of course, is desirable. Moreover, in the present construction, covers and pedestals of different sizes and designs may be variously 75 matched with each other, according as appears best. This not only makes for greater latitude in determining the appearance of the stand with reference to the display to be used, but also permits of one 80 stand component remaining in service should the other become unfit for this purpose. And when assembled, as shown, the appearance is harmonious, the effect being as of 85 a single integral structure.

I claim:

1. In a stand of the character described, the combination of a supporting pedestal having a flaring head provided around its margin with an upstanding peripheral wall forming a ledge at the point of juncture with the flaring head, a shelf mounted within the head and resting on said ledge below the upper edge of the peripheral wall, 90 a pan resting on the shelf with its sides in spaced relation to the peripheral wall, a pot centered within the pan and extending upwardly therefrom and above the peripheral wall, and a cover for the pot loosely surrounding the same and having its upper edge extended above and concealing the upper edge of the pot, the lower cover edge resting upon and being so fitted to the peripheral wall of the pedestal head as to 95 present the effect of being integral therewith, substantially as described.

2. In a stand of the character described, the combination of a supporting pedestal having a flaring head provided around its margin with an upstanding peripheral wall 100

forming a ledge at the point of juncture with the flaring head, a shelf mounted within the head and resting on said ledge below the upper edge of the peripheral wall, 5 a pan resting on the shelf with its sides in spaced relation to the peripheral wall, a pot centered within the pan and extending upwardly therefrom and above the peripheral wall, and a cover for the pot loosely 10 surrounding the same and having its upper

edge extended above and concealing the upper edge of the pot, the lower cover edge being outwardly flared and resting upon and being so fitted to the peripheral wall of the pedestal head as to present the effect of 15 being integral therewith, and the wall of the cover contacting the rim of the pan above the flared lower edge to effect a centering of the pan, substantially as described.

LOUIS WITTBOLD.
